US0D1054942S

(12) **United States Design Patent** (10) **Patent No.:** **US D1,054,942 S**
(45) **Date of Patent:** **** Dec. 24, 2024**

(54) **EXHAUST REDUCER ASSEMBLY**

(71) Applicant: **Shanghai Baidun Auto Parts Co., Ltd,**
Shanghai (CN)

(72) Inventor: **Xiaolei Zhu**, Shanghai (CN)

(**) Term: **15 Years**

(21) Appl. No.: **29/896,568**

(22) Filed: **Jul. 5, 2023**

(51) **LOC (14) Cl.** **12-16**

(52) **U.S. Cl.**
USPC **D12/194**

CLAIM

The ornamental design for an exhaust reducer assembly, as shown and described.

DESCRIPTION

FIG. 1 is an exploded top perspective view of an exhaust reducer assembly showing my new design;
FIG. 2 is an exploded bottom perspective view thereof;
FIG. 3 is an exploded front elevational view thereof;
FIG. 4 is an exploded rear elevational view thereof;
FIG. 5 is an exploded left side elevational view thereof;
FIG. 6 is an exploded right side elevational view thereof;
FIG. 7 is a top plan view of the unassembled exhaust reducer assembly as shown in FIG. 1;
FIG. 8 is a bottom plan view of the unassembled exhaust reducer assembly as shown in FIG. 2; and,
FIG. 9 is a perspective view of the exhaust reducer assembly of FIG. 1 shown in a fully assembled state.

1 Claim, 9 Drawing Sheets
